(57) **CLAIM**

The ornamental design for a contact sensor set, as shown and described.

DESCRIPTION

FIG. 1 is a perspective view of the contact sensor set showing my new design, including part 1 and part 2;

FIG. 2 is a front view of the contact sensor set depicted in FIG. 1;

FIG. 3 is a rear view of the contact sensor set depicted in FIG. 1;

FIG. 4 is a left side view of the contact sensor set depicted in FIG. 1;

FIG. 5 is a right side view of the contact sensor set depicted in FIG. 1;

FIG. 6 is a top view of the contact sensor set depicted in FIG. 1;

FIG. 7 is a bottom view of the contact sensor set depicted in FIG. 1;

FIG. 8 is a perspective view of part 1 of the contact sensor set depicted in FIG. 1, shown separately for completeness of illustration;

FIG. 9 is a front view of part 1 of the contact sensor set depicted in FIG. 1;

FIG. 10 is a rear view of part 1 of the contact sensor set depicted in FIG. 1;

FIG. 11 is a left side view of part 1 of the contact sensor set depicted in FIG. 1;

FIG. 12 is a right side view of part 1 of the contact sensor set depicted in FIG. 1;

FIG. 13 is a top view of part 1 of the contact sensor set depicted in FIG. 1;

FIG. 14 is a bottom view of part 1 of the contact sensor set depicted in FIG. 1;

FIG. 15 is a perspective view of part 2 of the contact sensor set depicted in FIG. 1, shown separately for completeness of illustration;

FIG. 16 is a front view of part 2 of the contact sensor set depicted in FIG. 1;

(Continued)

FIG. 17 is a rear view of part 2 of the contact sensor set depicted in FIG. 1;
FIG. 18 is a left side view of part 2 of the contact sensor set depicted in FIG. 1;
FIG. 19 is a right side view of part 2 of the contact sensor set depicted in FIG. 1;
FIG. 20 is a top view of part 2 of the contact sensor set depicted in FIG. 1; and,
FIG. 21 is a bottom view of part 2 of the contact sensor set depicted in FIG. 1.
The broken lines in the drawings are for the purpose of illustrating portions of the contact sensor set that form no part of the claimed design.
